UNITED STATES PATENT OFFICE.

JOHANNES BRETSCHNEIDER, OF WILSDRUFF, GERMANY.

INHALER.

1,264,607.

Specification of Letters Patent. Patented Apr. 30, 1918.

Application filed March 9, 1914. Serial No. 823,480.

To all whom it may concern:

Be it known that I, JOHANNES BRETSCHNEIDER, a subject of the King of Saxony, residing at Wilsdruff, Kingdom of Saxony, 5 German Empire, have invented certain new and useful Improvements in Inhalers, of which the following is a specification.

This invention relates to an inhalation apparatus that can serve for the inhalation 10 of air of different physical properties. The device itself, as well as its action, differs essentially from those usually known. While inhalation usually acts mainly chemically, certain materials being added thereto in 15 various forms, this present invention acts physically on the organism.

The invention is based on the following general principles. Every form of life is manifested by undulating lines—like the 20 pulsation of the blood. As summer alternates with winter, day with night, so in the human organism. A time of intense work alternates with quiet and inertia of the 25 organs; for instance in muscular work, molecular changes in the system, sleep, etc. This undulating or more strictly speaking alternating work keeps the system healthy and able to resist attacks, and is unquestionably necessary. Long-continued perfectly 30 regular and uniform life is simply inconceivable. Now this change of work can be effected either by natural or by artificial means, where the power of resistance of an organ is weakened, and especially against 35 infectious bacteria. Physical therapy has employed with great success for years alternating action on the skin, for instance in hydrotherapy. These physical effects represent the most important aids of the modern 40 healing art.

A similar physical action such as one uses on the skin by baths, compresses, etc., can be effected in the lungs and respiratory passages by my inhalation device. This is done 45 by alternately breathing two sorts of air—which act in opposite manners yet are able to counteract and equalize each other in their effects. Cold dry air and moist warm air are inhaled alternately, in such manner 50 that there is always an equalizing effect. The excessive absorption of the dry cold air is equalized by the moist warm air.

The invention is described and illustrated in the accompanying text and drawings, in

which similar characters represent similar 55 parts. Figure 1 shows one form of application in vertical axial section; Fig. 2 an alternate form; Fig. 3 a horizontal section on line 3—3 of Fig. 2. In Figs. 4 and 5 another form is shown in lengthwise and cross- 60 wise section respectively. Fig. 6 shows a detail of a perforated disk, an electro- motor, a compressed air conduit and certain proximate parts, said devices being used for effecting the vibration of the air. 65

The section illustrated by Fig. 5 is taken on the line 5—5 of Fig. 4.

In a cylindrical reservoir 1 there is in a lower section 2 room and admittance for a source of heat, of any desired nature. The 70 intermediate compartment 3 and the upper one 4 are insulated from each other and from without by partitions which are bad conductors of heat. The middle compartment is a water reservoir. The water may 75 be admitted by an opening of any suitable kind, not here shown, or through the circular pipe 5 having small perforations 6 in its side, which pipe usually admits compressed air or air at normal pressure 80 received through conduit 5^a, discharging such air in finely divided jets through said perforations into the space above the water level. These openings 6 can also be arranged somewhat below the water level; 85 and even at the bottom of the middle compartment 3, in order to compel the air to pass through the water.

The partition wall between the intermediate and the upper compartment is in the 90 form of an inverted cone perforated at the apex. In the center a pipe 7 leads upward as shown in Fig. 1. Near its lower end, in the water compartment, a jet 8 may discharge water spray against the air current 95 entering from below into the pipe 7. In the upper compartment there is a cooling reservoir 9, hung by hooks 10 in recesses in the outer wall, and which the pipe 7 pierces centrally from below upward. From this pipe 100 the water-saturated air coming from the water reservoir passes into the channels 11 and thence to the annular space of the reservoir 1 between the cooling reservoir 9 and the wall of the reservoir 1. In this manner 105 the air will deposit all the moisture which it contains, all of which will collect on the deepest part of the double bottom. Thence

the water will pass automatically through a spiral depression in the sleeve of the intermediate bottom which guides the pipe 7, back to the water chamber.

- 5 In the water chamber a space 12 is separated from the rest, to which there is an entrance 13, the mouth of which is so constructed that it permits the passage of air only from above downward.
- 10 Usually the apparatus has two outlets. The outlet 14 permits cold dry air to be drawn off through the pipe line 16 from the lower portion of the cooling chamber. But one can also arrange further air outlets 15 which may be thrown in and out of use, and which permit taking dry air directly out of the annular space, that is, that which is somewhat less cool; or warmer air from the space between the cooling chamber and the 20 cover (which space may be somewhat larger than here shown). Fig. 1 shows as a further alternative a by-pass 17 through the water chamber, to permit taking off dry air which is either hot or comparatively warm 25 by reason of the action of the heater in compartment 2.

The opening 15 permits taking off purified moist air.

In cases where it is desired to operate with 30 especially marked contrasts, the dry air can be led through an artificial cooling apparatus 19 by means of a pipe 18, said apparatus containing porous calcium chlorid or pentoxid of phosphorus, or similar hygroscopic material, and then through a filtering layer 20^a of cotton wool or the like.

In the places marked 20, 21, 22, 23 (Fig. 1) there are soft rubber tubes, which may be closed by pressure. These are shown in 40 20, 21 and 23, so that in the arrangement shown, dry air, which has been warmed, and further artificially dried, is taken off at 24.

In Figs. 2 and 3 is shown a modification of 45 my device.

The pipe 7 is removed from the center. As shown in Fig. 3, the central space is divided by partitions AB and MC, the upper space by partitions CD. The air passes upward through 7^a, then downward through 13^a, and finally, as shown, emerges under water. Thence it finds a further passage only through 7^b, upward, and then again through 13^b downward into contact with the 55 water, after which it can be taken off through 15, or sooner through 14.

In Figs. 4 and 5 there is in the interior of the cooler a second cooler, which permits attaining lower temperatures.

60 In the middle the tube 7 discharges downward. In the upper portion a cooling compartment 9 is hung by hooks 10 in recesses in the outer walls, and this receives the pipe 7 running spirally from below upward.

65 From this pipe the air coming from the

water-space passes into the annular space which remains between the cooling space 9 and the periphery of the chamber 1. In this passage the air deposits its moisture, which collects on the lowest portions of the intermediate bottom. Thence the moisture passes automatically through a spiral recess in the sleeve of the intermediate bottom, which guides the pipe 7, back to the water space. In the water space a space 12 is separated 70 from the rest, and in this a passage 13 enters, the mouth of which is so formed that it permits the passage of air only from above downward. The cooling compartment or reservoir 9 contains refrigerating material 75 arranged in vertical layers 15^a in the central part of said reservoir and surrounded by additional and coarser refrigerating material as shown in Fig. 4. The vertical layers 15^a contain a cooling mixture. From the 80 annular space the air passes through the pipe 16 into the space below said mixture, and between the layers, upward, where it is drawn off through 18 and 19. The water of condensation can pass out through the 85 spring valve 20^a.

Usually the apparatus has three discharge openings. The opening 18, Fig. 4, corresponding in function to outlet 14 of Figs. 1 and 2, lets cold dry air be taken directly out 90 of the drying device. There can also be further discharge openings, which can be thrown in and out of use, and which take the air directly out of the annular space, where it is less dry or cold. The drawing 95 shows in Fig. 4 an alternative pipe 19 having an indirect passage through the water space, said pipe being brought into proximity to the heater in compartment 2 and also immersed in the water heated thereby. 100 Of course the air within said pipe is heated by these agencies. Fig. 4 also shows a short outlet pipe 20^b corresponding to outlet pipe 15 of Fig. 1 which conducts warm moist air from the space above the water. The said 110 outlet pipes 18, 19 and 20^b make it easy to draw at will either cold dry air, warm moist air or warm dry air from the apparatus.

The use of the inhaling apparatus permits the physician, by the patient's alternately breathing warm moist and cold air, to effect thermic excitement of the respiratory passages and of the lungs. The action of a thermal excitement is much greater when a mechanical one is combined therewith. In order to enable this to be done also by inhalation, the fresh air which is introduced into the apparatus is set in vibration of predetermined strength, sufficient to transmit a certain amount of vibratory 115 action through the passages of the apparatus to the lungs of the patient. In breathing such vibrated air a mechanical excitement is produced in the respiratory passages and in the lungs. If for example infectious ele- 120 125 130

ments have settled in the lungs it is not impossible that this vibration of the lung tissues will hinder their development.

The vibration of the air can be effected, 5 for example, as shown in Fig. 6.

The compressed air conduit 5^a shown in this figure is interrupted by a disk 2^d, which has openings 2^e at intervals near its border and which is turned by an electric motor 3^a, 10 said openings being arranged to register intermittently with said conduit.

The compressed air conduit 5^a of Figs. 1, 4 and 6 may be divided in sections illustrated in this figure, having between them 15 an interrupting rotatable disk 2^d, which is provided at intervals with a circular series of openings 2^e individually registering with said conduit, which is closed by the intervening solid parts of said disk, so that said 20 disk alternately admits and cuts off the supply of air. This disk may be driven by a convenient electromotor 3^d.

The device for delivering the air can be affixed to the person breathing, by a forehead band, in order that he may take as little active part as possible in the treatment. 25 Instead of the usual mouth piece breathing, the air can be breathed as delivered by a regulatable current. By an arrangement of 30 tone-producing appliances, the air can be set in vibration with any desired degree of frequency. Also, the air to be inhaled can be subjected to the action of any desired radiations, in order to replace the natural 35 effect of the sun's rays. The appliance for effecting this can be placed either before or behind the inhalation apparatus.

Claims:

1. Inhalation apparatus comprising a heated water containing compartment, tubular means for supplying air and water to said compartment, a refrigerating compartment in proximity thereto and having a tubular connection therewith and means for drawing 45 from these compartments at will cold dry air, relatively warm moist air or relatively warm dry air.

2. Inhalation apparatus comprising a heated water-holding compartment, a refrigerating compartment, heat insulating material separating these two compartments, means for discharging air under pressure into said water-holding compartment, means for supplying water in contact with such air, a 50 tubular connection between the said compartments extending to the remoter parts of said refrigerating compartment, a tubu-

lar connection between the water compartment and the nearer warmer part of the refrigerating compartment and an additional tube from the latter part of the latter compartment passing through the water and air in the water compartment without communicating therewith but having an outlet, 60 said refrigerating compartment having an outlet for cold dry air and said water compartment having an outlet for warm moist air.

3. Inhalation apparatus comprising a heated compartment supplied with moist air and 70 water, a refrigerating compartment, an air pipe making connection between the two compartments, pipes conducting air from the refrigerating compartment respectively into and through the said heated compartment, and outlets whereby dry cold air, dry 75 warm air or moist warm air may be drawn from the apparatus at will.

4. Inhalation apparatus comprising a heated water containing compartment supplied 80 with air and a refrigerating compartment partly subdivided into a series of parallel sub-compartments, said apparatus being provided with means for obtaining cold dry 85 air, warm dry air or relatively warm moist air from it at will.

5. Inhalation apparatus comprising two compartments, one of which is moist and heated, the other being refrigerated, said apparatus being supplied with a current of 90 air having vibrations and interruptions and said apparatus being provided with means for drawing therefrom at will cold dry air, relatively warm dry air or warm moist air as preferred.

6. Inhalation apparatus comprising a heated water-containing and air-containing compartment, a refrigerating compartment in proximity thereto and having a tubular connection therewith provided with means permitting the flow of air from the refrigerating compartment through said connection to the heated compartment but not in the reverse direction and outlets for drawing at will either cold dry air directly from said 105 refrigerating compartment or warm moist air directly from the first mentioned compartment substantially as set forth.

In witness whereof I have signed this specification in the presence of two witnesses. 110
